Primary Examiner — Kevin K Rudzinski*Assistant Examiner* — Paul D Bohannon(74) *Attorney, Agent, or Firm* — James A. Sheridan; Sheridan Law, LLC(57) **CLAIM**

We claim the ornamental design for a staggered aircraft seats, as shown and described.

DESCRIPTION

FIG. 1 is a perspective view of a staggered aircraft seats, showing our new design, with a staggered formation of seats providing a wider seatback between two narrower seatbacks, and middle armrests with multiple tiers;

FIG. 2 is a front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The seat support portions, the outboard armrests, and the seat covers are shown in broken lines for illustrative purposes only and forms no part of the claimed design.
